his attys.

UNITED STATES PATENT OFFICE.

JAMES H. WICKES, OF NEW YORK, N. Y.

REFRIGERATOR-CAR.

SPECIFICATION forming part of Letters Patent No. 247,975, dated October 4, 1881.

Application filed May 26, 1881. (No model.)

To all whom it may concern:

Be it known that I, JAMES H. WICKES, a citizen of the United States, residing at New York, in the county and State of New York, 5 have invented new and useful Improvements in Refrigerators, of which the following is a specification.

This invention relates to an improvement on a refrigerator of that class which I have described in Letters Patent No. 230,376 granted to me July 20, 1880.

This invention is illustrated in the accompanying drawings, in which Figure 1 represents a side view of my refrigerator-car partly 15 in section. Fig. 2 is a cross-section in the plane $x x$, Fig. 1. Fig. 3 is a perspective view of the lower portion of the ice-chamber on a larger scale than the previous figures.

Similar letters indicate corresponding parts. 20 In the drawings, the letter A designates the provision-chamber, in this example constituting the body of a refrigerator-car. B is the ice-chamber; C D, the upper and lower ice-gratings, and G the inclined bottom plate of the ice-chamber.

By referring to Fig. 1 it will be seen that the upper grating, C, is roof-shaped, and from the bars of this grating are suspended wires a , whereby the drip-water on passing down from 30 the ice box is spread over a large evaporating-surface, and the cooling effect of this drip-water is thereby materially increased.

The lower grating, D, consists of two sets of wires, $b b'$, which extend from one side of the 35 car to the other in the lower narrow portion of the ice-box, and which cross each other and are inclined in opposite directions, as shown in Fig. 3, so that small pieces of ice dropping down through the upper grating will be retained on this lower grating and that the drip-water passing down from the wires a and from the inclined bottom plate, G, and also the drip-water resulting from the small pieces of ice 40 collected on said lower grating will run down over the wires $b b'$, whereby the same is distributed over a large evaporating-surface, so that its cooling effect is increased.

In the example represented by the drawings I have shown only one lower grating; but in 45 practice, and where the size of the lower por-

tion of the ice-chamber permits it, I propose to place two or more such gratings, one above the other, so that, as nearly as possible, all the drip-water is caught by the wires $b b'$ of the different gratings.

The inclined bottom G is supported by traverses F, so that the same cannot be injured by packages placed beneath.

The ice-chamber B is situated at one end of the provision-chamber A, and it has openings 60 c in its inner side, near its top, and openings d near its bottom, whereby air is admitted to the ice-chamber from the upper part of the provision-chamber, which, after having passed down through the ice-chamber, discharges 65 therefrom into the lower part of the provision-chamber. The lower or discharge openings are in a door, I, through which access is had to the lower part of the ice-chamber.

On the bottom of the ice-chamber B is a 70 waste-water pan, H, having an outlet-pipe, e, provided with a suitable trap.

I disclaim in this present application everything shown and described in my Patent No. 230,376.

What I claim as new, and desire to secure by Letters Patent, is—

1. The combination, with the ice-chamber B, of an upper grating, C, and a lower grating, D, (one or more,) said lower grating being constructed of inclined wires $b b'$, which cross each other, substantially as and for the purpose shown and described.

2. The combination, with the ice-chamber B and its grating C, of wires a , depending from 85 the bars of said grating, substantially as and for the purpose set forth.

3. The combination, with the ice-chamber B, its upper grating, C, and its lower grating, D, of wires a , depending from the bars of the upper grating, substantially as and for the purpose described.

In testimony whereof I have hereunto set, my hand and seal in the presence of two subscribing witnesses.

JAMES H. WICKES. [L. S.]

Witnesses:

J. VAN SANTVOORD,
CHAS. WAHLERS.
